UNITED STATES PATENT OFFICE.

CHARLES WACHTEL, OF BROOKLYN, NEW YORK, ASSIGNOR TO INTERSTATE ELECTRIC NOVELTY CO., OF NEW YORK, N. Y., A CORPORATION OF NEW YORK.

PORTABLE ELECTRIC LIGHT.

1,206,274.

Specification of Letters Patent. Patented Nov. 28, 1916.

Application filed May 21, 1914. Serial No. 839,936.

To all whom it may concern:

Be it known that I, CHARLES WACHTEL, a citizen of the United States, and a resident of Brooklyn, in the county of Kings and State of New York, have invented certain new and useful Improvements in Portable Electric Lights, of which the following is a specification.

The invention pertains more particularly to improvements in the class of electric lamps designed to be held in the hand and sometimes used as flash lights and at other times for affording a permanent light for a short period, and the object of the invention is to provide a novel and efficient construction of lamp of the class referred to, the novelty residing, in part, in a new arrangement of those portions of the lamp through which the circuit is made for lighting the same and in the new circuit closer mechanism and in the manner of securing the reflector for the lamp.

The invention will be fully understood from the detailed description hereinafter presented, reference being had to the accompanying drawings, in which:

Figure 1 is a side elevation of a portable electric light embodying my invention; Fig. 2 is a central vertical section on a larger scale of the same; Fig. 3 is a corresponding section, partly broken away and on an enlarged scale, through the upper end portion of the electric light; Fig. 4 is an enlarged horizontal section, partly broken away, through the light taken on the dotted line 4—4 of Fig. 1, and Fig. 5 is a side elevation, partly broken away, of the central portion of the exterior casing of the light, with the circuit closer or switch omitted, this figure being presented to illustrate the manner of exposing the two circuit conductors at their adjoining ends so that the circuit closer when manually operated may connect said ends for completing the circuit through the lamp.

In the drawings 10 designates a paper or fiber casing for the flash light, 11 the battery therein, 12 the lens, 13 the electric lamp bulb, 14 the reflector, 15 the usual connection of the battery with the lamp, and 16 the usual electrical conductor connection between the lower metallic cap 17 and the lower terminal of the battery 11. The casing 10 is equipped with two conductors or strips of metal 18, 19, the lower end of the

conductor 19 being in electrical connection with the metal cap 17, as usual, and which cap is ordinarily screwed upon a metal sleeve fastened around the lower end of the casing 10. The upper end of the conductor 18 is in electrical connection with the reflector 14 through the medium of a concealed metal band 20 which I secure within the upper end of the casing 10 and so shape the same that its sides converge downwardly and inwardly and form a seat to detachably receive and engage the exterior surface of the said reflector 14. The upper edge of the reflector 14 is flanged outwardly and may rest upon the upper edge of the non-conducting casing 10, and over the upper edge of the reflector 14 and resting thereon is the lens 12, said lens being secured as usual by means of an upper threaded cap 21, secured upon the upper end of the casing 10 and having an inwardly turned annular flange 22 which engages the upper edge portions of the lens 12 and serves as a clamping means for binding the lens firmly upon the reflector 14.

Ordinarily, in flash lights as heretofore used, there has been an electrical connection between the cap 21 and conductor 18, but in this instance and as a part of my invention there is no electrical connection between the cap 21 and conductor 18, and it may be seen on reference to Fig. 3 that the upper end of the conductor 18 is bent inwardly and secured by soldering or the like to the band 20, and that therefore the circuit from the battery and lamp to the conductor 18 will be through the reflector 14 and band 20, the cap 21 being entirely out of the electric circuit. Ordinarily the reflector 14 has been in electrical connection with the cap holding the lens, but in this instance it is to be observed that the upper end of the reflector is separated from the cap 21, said cap being at the outer side of the casing 10 and the flange 22 thereof being carried outwardly in the horizontal plane of the upper edge of the casing 10 and then upwardly and inwardly to engage the lens 12.

The casing 10 is preferably formed from a spirally wound sheet of fiber, and the conductors 18, 19 in one continuous piece are wound within said sheet during the formation of the tube or casing 10, and thereafter a V-shaped recess 23 is formed in the ex-

terior wall of the casing 10 and extended through the metal strip intended to form the conductors 18, 19, as illustrated in Fig. 5. The formation of said recess 23 and extending it through the metal strip serves to sever said strip and leave the adjacent ends of the sections thereof, said sections forming the conductors 18, 19, separated from each other by a narrow space and exposed at the walls of the recess to be engaged by the circuit closer, which at the proper time is utilized for placing said exposed ends of the conductors 18, 19 into electrical connection with each other, thereby to complete the circuit through the lamp. The lower end of the conductor 19 is placed in electrical connection with the cap 17 and the sleeve on which said cap is screwed in the customary way by means of an eyelet or rivet 24. The upper end of the conductor 18 becomes exposed by recessing the casing 10, as at 25, in line with said conductor and then bending the upper end of the conductor inwardly, as shown in Fig. 3, to be fastened to the band 20.

The circuit closer or switch mechanism comprises the transverse casing 26 riveted to the shell or casing 10 and forming therein a chamber 27 for the leaf spring 28, said spring 28 having secured to it a buttonhead 29, and said casing 26 being provided with a slot 30 in which the shank of the buttonhead 29 may be manually moved and the ends of which slot limit the movement of the buttonhead 29 and the spring 28 connected therewith. The spring 28 bears at both ends against the casing 10, and one end of said spring is curved on convex lines, as at 31, to ride smoothly against the surface of the casing 10, and the other end of said spring 28 is formed with a longitudinal V-shaped portion 32 forming therein an approximately V-shaped recess 33, as shown in Fig. 2. The V-shaped portion 32 of the spring 28 is the part of said spring provided for electrically connecting at the proper time the adjacent ends of the conductors 18, 19, and said portion 32 of said spring is adapted for movement in the recess 23 of the casing 10 and of lying against and connecting the exposed adjacent ends of the conductors 18, 19 at the base of said recess, the apex of the V being adapted to form an efficient electrical connection between the conductors 18, 19 and rendering it unnecessary to bend the ends of said conductors outwardly. When the spring 28 is in one position with the buttonhead 29 at one end of the slot 30, as shown in Fig. 4, the spring circuit closer 28 will have its end 32 so positioned that it cannot engage the adjacent ends of the conductors 18, 19, and at such time the lamp 13 will be dark and there will be no circuit through the lamp and battery. When the button-

head 29 is pushed to the other end of the slot 30 it moves the spring 28 until the V-shaped end 32 thereof is between and in engagement with the adjacent ends of the conductors 18, 19, and at such time the circuit 70 will be completed from the lower end of the battery through the conductor 16, cap 17, conductor 19, spring circuit closer 28, conductor 18, band 20, reflector 14 and lamp socket to the upper end of the battery. 75

Ordinarily it has been customary in the construction of flash lights of the character in question to rivet the casing of the circuit closer spring to a conductor corresponding with 19 and have one end of the circuit 80 closer spring in electrical connection with its casing, and in this way said casing was always in electrical connection with the lower exposed cap 17; and it was also customary to connect the upper end of a conductor corresponding with 18 with the cap 85 21, with which the reflector for the lamp was in electrical connection, and under these circumstances it is plain that a metal tool, such as a screw driver lying against the circuit 90 closer casing and upper cap or against the lower cap and upper cap of the flash light, would make the circuit and result in the battery being unnecessarily consumed. 95

It will be observed that in accordance with 95 my invention the circuit closer casing is not riveted to or in electrical connection with either of the conductors 18, 19, and therefore that there is no normal electrical connection between said casing and the lower cap 17. 100 The upper cap 21 is not at any time in circuit, and hence the flash light as a whole may be placed in a tool box or with any metal articles without danger of the circuit being accidentally made by the contact of the 105 flash light with the blade of a tool or the like.

What I claim as my invention and desire to secure by Letters Patent, is:

1. A portable electric light of the class described comprising an exterior casing containing a battery and having at its upper end an electric lamp in electrical connection with said battery, circuit terminal conductors extending along said casing normally separated from each other at adjacent ends and one of which is in electrical connection with the lamp and the other with the battery, and circuit closing means for electrically connecting the adjacent ends of said terminal conductors comprising a closer-casing 110 on the exterior main casing and insulated from both said terminal conductors and a conductor therein adapted on being moved for the purpose to engage said ends of the terminal conductors, said terminal conductors being embedded within the material of 115 said main casing and said main casing being recessed at the adjacent ends of said conductors and thereat exposing said ends to be engaged by the circuit closer conductor. 120 125

2. A portable electric light of the class described comprising an exterior casing containing a battery and having at its upper end an electric lamp in electrical connection with said battery, circuit terminal conductors extending along said casing normally separated from each other at adjacent ends and one of which is in electrical connection with the lamp and the other with the battery, and circuit closing means for electrically connecting the adjacent ends of said terminal conductors comprising a closer-casing on the exterior main casing and insulated from both said terminal conductors and a conductor therein adapted on being moved for the purpose to engage said ends of the terminal conductors, said terminal conductors being embedded within the material of said main casing and said main casing having an approximately V-shaped recess at the adjacent ends of said conductors and thereat exposing said ends to be engaged by the circuit closer conductor, which has an approximately V-shaped portion adapted to said recess.

3. In a portable flash light of the character described a casing containing a battery and an electric lamp, circuit closing means comprising circuit terminal conductors extending along said casing in line with each other and normally separated from each other at adjacent ends, an escutcheon on the exterior of said casing and insulated from both said conductors and a manually operative conductor adapted on being moved for the purpose to engage and electrically connect said ends of said terminal conductors, said terminal conductors being embedded within the material of said casing and said casing being recessed at the adjacent ends of said terminal conductors and thereat exposing said ends, and said manually operative conductor being a spring associated with an exposed slide mounted on said escutcheon.

Signed at Brooklyn, in the county of Kings and State of New York, this 19th day of May, A. D. 1914.

CHARLES WACHTEL.
